US0D1049276S

(12) **United States Design Patent** (10) Patent No.: **US D1,049,276 S**
(45) Date of Patent: ** Oct. 29, 2024

(54) **LEG EXERCISER**

(71) Applicant: **Zuhong Shi**, Zhejiang (CN)

(72) Inventor: **Zuhong Shi**, Zhejiang (CN)

(**) Term: **15 Years**

(21) Appl. No.: **29/953,146**

(22) Filed: **Jul. 19, 2024**

(51) LOC (14) Cl. **21-02**

(52) U.S. Cl.

USPC **D21/692**

(58) **Field of Classification Search**

USPC D21/692, 662, 694, 673, 684, 679, 693;
482/112, 124, 126, 127

CPC A63B 21/0004; A63B 21/0455; A63B
21/4047; A63B 23/0488

Primary Examiner — Ryan Harvey

(57) **CLAIM**

The ornamental design for a leg exerciser, as shown and described.

DESCRIPTION

FIG. 1 is a perspective view of the leg exerciser showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is another perspective view thereof.

1 Claim, 8 Drawing Sheets
